SUCTION CLEANING APPARATUS

Charles H. Taylor, Springfield, Mass., assignor to Westinghouse Electric & Manufacturing Company, East Pittsburgh, Pa., a corporation of Pennsylvania

Application March 27, 1943, Serial No. 480,735

8 Claims. (Cl. 15—9)

My invention relates to a suction cleaner and more particularly to a convertible suction cleaner capable of being used as a handle-propelled cleaner or as a tank-type cleaner and which, in the latter position, is adapted for on-the-floor cleaning, for off-the-floor cleaning, and for blowing.

One object of my invention is to produce an improved cleaner of the type set forth.

A further object of my invention is to produce a cleaner which can be converted from one use to another by a simple adjustment of a built-in converting mechanism.

A still further object of my invention is to produce a suction cleaner in which the adjustment of the converter to off-the-floor cleaning or blowing automatically raises the rotary agitator of such cleaner out of contact with the floor covering, or other supporting surface, and in which readjustment of said cleaner to its floor-cleaning position also automatically returns the rotary agitator to its original position.

These and other objects are effected by my invention as will be apparent from the following description and claims taken in connection with the accompanying drawings, forming a part of this application, in which:

Fig. 1 is a view, partly in side elevation and partly in section, of a suction cleaner embodying my invention, the same being shown in floor-nozzle cleaning position;

Fig. 2 is a view similar to Fig. 1 showing the cleaner in attachment suction cleaning position;

Fig. 3 is a view similar to Fig. 2 showing the cleaner in attachment blowing position;

Fig. 4 is a view similar to Fig. 1 showing a modified form of construction;

Fig. 5 is a fragmentary side elevational view showing the position of the valve and brush roll actuating elements when the apparatus is used for floor nozzle cleaning;

Fig. 6 is a view similar to Fig. 4 showing the apparatus in attachment blowing position;

Fig. 7 is a view similar to Fig. 5 showing the position of said elements when the apparatus is used for attachment blowing;

Fig. 8 is a view similar to Figs. 4 and 6, showing the apparatus in attachment cleaning position;

Fig. 9 is a view similar to Figs. 5 and 7, showing the position of said elements when the apparatus is used for attachment cleaning;

Fig. 10 is a fragmentary bottom plan view of the cleaner;

Fig. 11 is a diagrammatic view of the switch which actuates the brush roll; and,

Fig. 12 is a sectional view on line XII—XII of Fig. 1 or 4.

Figs. 1 to 3

5 Referring to the drawings and particularly to the embodiment illustrated in Figs. 1 to 3, I show a suction cleaner comprising a casing 16, having supporting wheels 18 and 20 and a propelling handle 22. The casing 16 is provided with a floor nozzle 24, a dust bag 26, and a suction creating device 28. The dust bag 26 is accessible for emptying by removing a detachably secured and preferably decorative cover 30. The floor nozzle 24 is provided with a rotary agitator 32 and communicates with the dust bag 26, through a passage 34 and a throat 35. The low pressure side of the suction creating device 28 communicates with the nozzle 24, through the dust bag 26, and the high pressure side of the suction device communicates with a compartment 36. The exhaust air in the compartment 36 is discharged to the atmosphere through an outlet opening 40 formed in the wall of the compartment 36 and a discharge outlet 41 in the outer wall of the casing 16.

10 In order to render the suction cleaner convertible from floor-nozzle cleaning to attachment cleaning or to attachment-hose blowing, I provide a duct 42 which is slidable in a guide opening 30 formed by the bottom wall 43 of the compartment 36, the bottom wall portion 44 of the casing 16 and side walls 45 and 46 (see Fig. 12). While this is a preferred form of construction, it is to be understood that any other supporting and guiding means for the duct 42 may be employed. At its inner end, the passage 34 is provided with a valve 48 which is normally biased into the position shown in Fig. 1 by a spring 50. The outer end 52 of the duct 42 is adapted to be connected to one end of an attachment hose 54, the other end of which carries a floor nozzle or other cleaning tool (not shown). The bottom wall 43 of the compartment 36 is provided with an opening 56 which is adapted to register with 15 a similar opening 58 formed in the upper wall of the duct 42. The upper wall of the duct 42 is also provided with a projection or lug 60 which is slidable in an opening 62 in the wall 43. The lug 60, in one position of the duct 42, serves as 20 a shutter and coacts with a pendant wall 64 to close the opening 40 so as to prevent passage of air from the compartment 36 to the atmosphere, as shown in Fig. 3. In order to facilitate assembly of the duct 42, the bottom wall portion 44 25 is detachably secured in position as at 66. The

duct 42 is provided with an end portion 68, which, when the duct 42 is in its innermost position, actuates the valve 48 against the action of the spring 50, or from the position shown in Fig. 1 to the position shown in Fig. 2.

OPERATION

Figs. 1 to 3

When it is desired to use the cleaner for floor-nozzle cleaning, the duct 42 is adjusted to the position shown in Fig. 1 in which the openings 56 and 58 are out of registration. The end 68 of the duct 42 is out of contact with the valve 48 and the projection 60 is out of contact with the pendant wall 64. When the cleaner is in operation, the air flows through the nozzle 24, passage 34 and bag 26 into the compartment 36 and out through the outlet openings 40 and 41, as shown by the arrows in Fig. 1.

When it is desired to use the cleaner for attachment cleaning, the attachment hose 54 is connected to the end 52 of the duct 42 and the duct is moved to its innermost position, as shown in Fig. 2. In this position, the valve 48 closes the passage 34 and establishes communication between the interior of the duct 42 and the suction creating device 28, through the throat 35 and the dust bag 26. It will be noted that the openings 56 and 58 are again out of registration, and that the lug 60 is spaced from the wall 64 so that the opening 40 is not obstructed. The air now flows through the duct 42, throat 35, dust bag 26, compartment 36 and outlets 40 and 41, as shown by the arrows in Fig. 2.

When it is desired to use the apparatus for blowing air through the attachment hose 54, the duct 42 is pulled out to its outermost position, as shown in Fig. 3. In this position, the openings 56 and 58 are in registration and the projection 60 abuts against the pendant wall 64, thus interrupting communication between the compartment 36 and the atmosphere, through the openings 40 and 41. The air now flows through the nozzle 24, passage 34, throat 35, dust bag 26, compartment 36, and openings 56 and 58, and out through the duct 42, as shown by the arrows in Fig. 3.

When the apparatus is used for attachment suction cleaning as shown in Fig. 2, or for blowing as shown in Fig. 3, the brush roll 32 is preferably raised out of contact with the surface being cleaned by any suitable means, one form of which is illustrated and will be described in connection with the embodiment shown in Figs. 4 to 9.

Figs. 4 to 9

In Figs. 4 to 9, inclusive, I show another embodiment of my invention in which automatic means are provided for actuating the valve 48 and for raising the agitator 32 out of contact with the floor covering or other supporting surface while the cleaner is used for attachment-hose cleaning or for blowing.

In order to actuate the valve 48, I provide one wall 69 of the duct 42 with a pin 70 which is slidable in a slot 72 formed in the adjacent vertical wall 45 of the guide opening. I also provide, on the exterior of said wall 45, a lever 74, fulcrumed at 75 and provided with notches 76, 78 and 80. The lever 74 is constantly biased into engagement with the pin 70 by a spring 82 and is connected to the valve 48 by a crank arm 86. It will be noted that in this modified form the end portion 68 of the duct 42 is omitted so

that, in its innermost position, the duct 42 is out of contact with the valve 48.

In order to raise the agitator 32 out of contact with the floor covering, I provide the side 59 of the duct 42 with another pin 88 which slides in a slot 90 formed in the wall 45 of the duct 42. I also provide another lever 92, fulcrumed to the wall 45 at 94, and provided with notches 96, 98, and 100. The lever 92 is constantly biased into engagement with the pin 88 by a spring 102. The lever 92 is provided with a tip or extension 104 which is adapted to actuate a spring switch 106. The spring switch 106 is constructed as to assume a normally open upper position A, and is adapted to be depressed into a lower closed position B, as shown in Figs. 5 and 11. The spring switch 106 is connected through wires 107 to a solenoid 108. The agitator 32 is carried by an arm 110, which is pivoted at 112 and which is connected at its other end to the plunger or core 113 of the solenoid 108. A spring 114 biases the arm 110 upwardly to raise the agitator, while the solenoid 108, when energized, actuates the arm 110 downwardly against the tension of the spring 114, to bring the agitator into contact with the surface being cleaned.

OPERATION

Figs. 4 to 9

When the cleaner is to be used for floor-nozzle cleaning, the duct 42 is moved to its central position, as shown in Fig. 4. In this position of the duct 42, the lever 74 assumes the position shown in Fig. 5, with the pin 70 engaging the notch 78. The valve 48 remains in the position shown in Fig. 4. Also, in this position of the duct 42, the lever 92 assumes the position shown in Fig. 5 in which the pin 88 engages the notch 98 and the tip 104 of the lever 92 depresses the switch 106 from its upper open position at A to its lower closed position at B to complete the circuit through the wires 107 and energize the solenoid 108. The plunger 113 is now pulled downwardly and brings the agitator 32 into contact with the surface being cleaned. The air now travels through the nozzle 24, dust bag 26, compartment 36, and out through the outlets 40 and 41, as shown by the arrows in Fig. 4 and as described in connection with Fig. 1.

When it is desired to use the apparatus for blowing through the hose 54, the duct 42 is moved into its innermost position, as shown in Fig. 6. This moves the levers 74 and 92 to the position shown in Fig. 7. In this position, the pin 70 engages the notch 76. Since the notch 76 is in lineal registration with the notch 78, the position of the lever 74, vertically considered, has not been changed and the valve 48 remains in the position it occupied in Fig. 4. As further shown in Fig. 6, the openings 56 and 58 are now in registration and the lug 60 is in contact with the pendant wall portion 115 to interrupt communication between the compartment 36 and opening 41. The air now flows through the nozzle 24, dust bag 26, compartment 36, openings 56 and 58, and out through the duct 42 and hose 54, as shown by the arrows in Fig. 6 and as described in connection with Fig. 3. Also, in this position of the duct 42, the pin 88 engages the relatively deep notch 100. This permits the lever 92 to tilt about the fulcrum 94, under the force of the spring 102, to raise the tip 104 thereof from engagement with the spring switch 106 which now resumes its upper open position at A. The opening of the switch 106 deenergizes the

solennoid 108 and the spring 114 raises the agitator 32 out of contact with the surface being cleaned.

When it is desired to use the apparatus for attachment suction cleaning, the duct 42 is moved to its outermost position, as shown in Fig. 8. The levers 74 and 92 now occupy the position shown in Fig. 9. In this position, the pin 70 engages the shallow notch 80. This causes the lever 74 to tilt about its fulcrum 84 and actuate the crank arm 86 to move the valve 48 to close the passage 34 and establish communication between the duct 42 and the throat 36. The air now travels through the hose 54, duct 42, throat 35, dust bag 26, compartment 36, and outlets 40 and 41 as shown in Fig. 8 and as described in connection with Fig. 2. The movement of the duct 42 to its outermost position also causes the pin 88 to engage the deep notch 96. In this position, the lever 92 is again tilted so that the tip 104 remains out of contact with the spring switch 106 which will remain in its upper open position. With the switch 106 open, the solennoid 108 remains deenergized and the agitator 32 remains in its raised position.

The notches 76, 78, 80, 96, 98, and 100 are suitably rounded so as to permit the pins 70 and 88, respectively, to move from one notch into the other when the duct 42 is positively moved, but the strength of the springs 82 and 102 is such as to retain the duct 42 in the position to which it is adjusted with sufficient force to prevent its accidental or unintended movement.

When the apparatus is used for attachment cleaning, the operator tends to pull the apparatus about by the hose 54, as is the common practice in the well-known tank type cleaner. In order to insure against dislodgment of the duct 42, I have so arranged the structure of Fig. 8 that for attachment cleaning the duct 42 is pulled outwardly until the projection 60 reaches the end of the slot 62, which forms a definite stop limiting the movement of the duct 42.

It will thus be seen that I have devised a simple and efficient converting mechanism which is built into the cleaner, and which is capable of converting the cleaner from floor-nozzle cleaning to attachment cleaning or to blowing, by the mere adjustment of the duct 42. Also, while the hose 54 is shown and described as a separate or detachable element, it is to be understood that it can be permanently connected to, or made integral with the end 52 of the duct 42, if so desired.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are specifically set forth in the appended claims.

What I claim is:

1. In a cleaner of the character stated, a casing, a suction-creating device therein, said casing having a nozzle communicating with the suction side of said device and having an outlet communicating with the discharge side of said device, a rotary agitator in said nozzle adapted to act on the surface being cleaned, a duct carried by said casing and movable into a plurality of operative positions, means actuated by movement of said duct into one operative position to interrupt communication between said nozzle

and said casing and to establish communication between the suction side of said device and said duct, means operable by movement of said duct into another operative position to close said outlet and establish communication between the discharge side of said device and said duct, and means operable by movement of said duct into either of said operative positions for raising said agitating device out of contact with said surface.

2. In a suction cleaner of the character stated, a casing, a suction-creating device therein, said casing having a nozzle and a passage connecting the nozzle to the suction side of said device, there being an outlet leading from the discharge side of said device to the atmosphere, a duct slidably against a wall of said casing on the discharge side of said device, said duct having an opening therein adapted in one operative position of said duct to register with an opening in said wall of said casing to establish communication between said duct and the discharge side of said device, means for closing said outlet when said opening in said wall of said casing is in registration with said opening in said duct, a valve disposed in said passage and normally separating said duct from the suction side of said device and means operable by the movement of said duct into another operative position to actuate said valve to close said passage and establish communication between the inner end of said duct and the suction side of said device.

3. In a cleaner of the character stated, a casing, a suction-creating device therein, said casing having a nozzle communicating with the suction side of said device and an outlet communicating with the discharge side of said device, a rotary agitator mounted for vertical movement in said nozzle, means for normally retaining said agitator in an upper position, out of contact with the surface to be cleaned, a duct carried by said casing and movable into a plurality of operative positions, means operative by movement of said duct into one operative position for diverting suction from said nozzle into said duct, means operative by movement of said duct into another operative position for closing said outlet and establishing communication between the discharge side of said device and said duct, and means operative by movement of said duct into still another position for moving said agitator downwardly into contact with said surface and re-establishing communication between said nozzle and said suction device and for opening said outlet.

4. A suction cleaner including a body having a nozzle extending across the front thereof, a fan motor unit at the rear of the cleaner, a filter chamber disposed between the fan motor unit and the nozzle, said filter chamber having an air filter therein and having an inlet at the bottom said body having a first passage extending from said inlet to said nozzle and a second passage extending rearwardly from said inlet and adapted to be connected to a flexible hose or the like, a discharge chamber communicating with the outlet of said fan motor unit and disposed adjacent said unit and said second passage, valve means for selectively connecting said inlet to said first passage or said second passage and closing communication with the other, and valve means for selectively connecting said discharge chamber with either the atmosphere or said second passage and closing communication with the other.

5. In a suction cleaner, a casing having a noz-

zle, a suction-creating device in said casing, a filter through which air moved by said suction-creating device is adapted to pass, there being an outlet leading from the discharge side of said filter and said suction-creating device to the atmosphere, a duct carried by said casing and adapted to be connected to an attachment hose, a valve for selectively connecting said nozzle or said duct to the low-pressure side of said suction-creating device, valve means for selectively connecting said outlet or said duct to the discharge side of said filter and said suction-creating device, and means operable by movement of said duct to actuate said valve and said valve means to place said low-pressure and said discharge side of said suction-creating device in communication, respectively, with said nozzle and with the atmosphere, in one position of said duct, with said duct and with the atmosphere in a second position of said duct, and with said nozzle and with said duct in a third position of said duct.

6. A suction cleaner comprising a casing, a suction-creating device therein, said casing having a suction inlet and a discharge outlet, a wall structure defining a passage adjacent a wall of said casing, a valve for selectively connecting said inlet or said passage to the low-pressure side of said suction-creating device, there being an opening in said wall of said casing leading from the high-pressure side of said suction-creating device into said passage, a plate slidable longitudinally against said wall and normally closing said opening, said plate having an opening therein adapted, in one position of said plate, to register with the opening in said wall to establish communication between the high-pressure side of said suction-creating device and said passage, means carried by said plate and adapted, in said position thereof, to close said outlet, and means

operable by movement of said plate and adapted, in another position of said plate, to actuate said valve into a position closing said inlet from the low-pressure side of said suction-creating device and establishing communication between said passage and the low-pressure side of said suction-creating device.

7. The structure recited in claim 6 in which said second means includes an arm carried by said plate and movable in said passage.

8. A suction cleaner comprising a casing, a suction-creating device therein, said casing having a suction inlet and a discharge outlet, a wall structure defining a passage adjacent a wall of said casing, there being an opening in said wall of said casing leading from the high-pressure side of said suction-creating device into said passage, a member slidable longitudinally against said wall into a first, a second or a third position, said member closing said opening in said wall in said first and second positions thereof and having an opening therein adapted, in said third position of said member, to register with said opening in said wall to establish communication between the high-pressure side of said suction-creating device and said passage, means operable by movement of said member to said third position to close said outlet, a valve for selectively connecting said inlet or said passage to the low-pressure side of said suction-creating device, means for positioning said valve to shut said passage off from the low-pressure side of said suction-creating device in said first and third positions of said member and for positioning said valve to shut said inlet off from, and to connect said passage to, the low-pressure side of said suction-creating device when said member is moved to said second position.

CHARLES H. TAYLOR.
